UNITED STATES PATENT OFFICE

CHARLES P. WELLMAN, OF WEST MEDFORD, MASSACHUSETTS

RECEPTACLE

Application filed March 4, 1930. Serial No. 433,009.

This invention relates to receptacles having more than four side faces and an end wall, of any suitable material usually paper or cardboard, and to flat and partially folded or closed blanks capable of being formed into such receptacles. When I refer to a "receptacle" in this specification, I do not exclude such receptacles as caps, cups, covers, trays, or carton having an open side top or bottom.

This invention aims to provide receptacles having more than four side faces, and hence possessing any or all of the advantages of such receptacles of wide adaptability to contain non-rectangular objects, of novelty and distinctiveness of shape, or of economy in wall area relative to volume enclosed, but which nevertheless are capable of easy and rapid manufacture by automatic machinery, are particularly adapted for easy and tight closure, and sealing if desired, and are neat in appearance, avoiding when desired any necessity of exposed flaps, flanges or exterior surface irregularities or lines of weakness and disfigurement which interfere with the affixing or imprinting of advertising or decorative matter smoothly on the outer faces of the receptacle.

Receptacles of which adjacent side walls form obtuse interior angles and which are made according to my invention are particularly adapted to serve as protecting receptacles for fragile articles, the manner of disposal of the receptacle material affording improved strength and rigidity.

Other objects and advantages of the invention will appear from this explanation of my invention and of typical species of receptacles and receptacle-forming blanks exemplifying my invention and shown in the accompanying drawings.

My invention is of particular utility in providing receptacles having an end intimately connected with more than four side walls, receptacles according to my invention having, if desired, side walls and an end so tightly sealed or otherwise fastened together as to be substantially free from leakage through the joints.

In the drawings:

Fig. 1 shows a plan view of a blank according to my invention;

Figs. 2, 3 and 4 are schematic perspective views illustrative of a preferred order of folding and affixing various sections of the blank to form finally the receptacle of Fig. 4;

Fig. 5 is a perspective view of the receptacle completely closed;

Fig. 6 shows in plan an alternate form of blank according to my invention;

Fig. 7 is a perspective view of a receptacle formed from the blank of Fig. 6;

Fig. 8 is a plan view of another form of blank according to my invention;

Fig. 9 is a perspective view of an open receptacle formed from the blank of Fig. 8;

Fig. 10 is a perspective view of the receptacle of Fig. 9;

Fig. 11 is a sectional view taken on the line 11—11 of Fig. 10;

Fig. 12 is a plan view of a collapsed tube which may be made from the blank of Fig. 8 in connection with an alternate method of forming a receptacle therefrom;

Fig. 13 is a perspective view of the tube of Fig. 12 when opened;

Figs. 14, 15 and 16 are perspective views similar to Fig. 13 and illustrating an order of folding parts of the blank to form a closed receptacle such as shown in Fig. 10; and

Fig. 17 is a plan view of an alternate form of blank according to my invention.

In the illustrated embodiments of my invention I have provided eight sided receptacles. It will be understood that these embodiments having eight sides are illustrative of a large number of receptacles having an end and more than four side faces, and which may be made according to my invention.

Referring to Fig. 1, the blank shown therein formed of an integral sheet of foldable material, such as paper or cardboard, includes a polygonal end section 11 having more than four sides adapted to define one complete end face of the desired receptacle having more than four sides, the shape of this end section corresponding to the cross-sectional shape of the receptacle, in the illustrated embodiments that of a regular octagon. A plurality of

side wall sections are provided at least equal in number to the sides of the polygonal end section 11, and having widths at their ends respectively equal to the lengths of the corresponding sides of the polygonal end section. Since in the present embodiment of the invention the polygonal end section is in the form of a regular octagon, at least eight side wall sections are provided, and are herein shown as having their ends corresponding in width to the length of a side of the octagonal end section.

At least two of the side wall sections thus provided are each directly integrally and flexibly joined at their ends to respective sides of the polygonal end section. In the illustrated embodiment of the invention two such side wall sections 12 and 13 are thus directly joined to sides of the polygonal end section 11, preferably as shown, to its opposite sides, the junction lines being defined by fold lines of increased flexibility 40 and 41. Other side wall sections of the blank not thus directly and flexibly joined to sides of the polygonal end section, but necessary to form a completely enclosing set of side walls are flexibly joined at their sides along fold lines of increased flexibility to one or the other of the side wall sections thus directly joined to the polygonal end section. A group or groups of conjoined side wall sections may therefore during closing of the blank into a receptacle be erected as a unit relative to the polygonal end section 11 and there folded around this end section.

Preferably as shown, the side wall sections are disposed in two groups, one of which includes the side wall section 12, and the other of which includes the side wall section 13, these two groups being capable of being erected relative to the polygonal end section 11 and then fastened or connected together to form a continuous set of side walls.

To enable the side wall sections (herein shown as in two groups) to be affixed, for example as shown in Fig. 4 suitable overlapping sections adapted to connect adjacent side walls are employed. Preferably as shown, such overlapping sections are provided in the form of additional side wall sections similar to those necessary for defining the side faces of the receptacle, and, in the erected position of the receptacle conform to and overlap other side wall sections. Accordingly, as shown in Fig. 1, the blank for forming the desired octagonal receptacle is provided with side wall sections in addition to the eight side wall sections necessary to define the side faces of the receptacle, in the present instance side wall sections 14, 16, 18, 20, 22, and 24 being flexibly connected to each other and to side wall section 12, and side wall sections 15, 17, 19, 21, 23, and 25 likewise being flexibly connected to each other and to side wall 13. In this way joints between groups of

side wall sections may be formed by the overlapping of full-sized side wall sections, thus avoiding exposed flaps or flanges on the exterior of the side walls of the receptacle.

The blank is capable of being formed into an open ended carton such as shown in Fig. 4, by erecting, folding around the polygonal end section 11, and fastening together, the various side wall forming elements of the blank. This may conveniently be accomplished by first applying adhesive to elements which are intended to overlap, then moving the blank as a whole relative to folding instrumentalities capable of erecting the two groups of side wall sections relative to the polygonal end section, folding and overlapping them into a tube, and lastly applying a compression to the overlapped joints. Normally the specific instrumentalities suitable for these operations comprise a reciprocating plunger generally conforming to the end and inner side faces of the receptacle, various movable or fixed abutments disposed around the plunger and capable of contacting with the side wall-forming elements of the receptacle to wrap them around the plunger as the plunger moves with respect to these abutments, and inwardly moving compressor surfaces adjacent the path of the plunger for applying the above mentioned compression to the overlapping joints. Obviously if only the two side wall sections 12 and 13 of the receptacle were connected to the end section where they abut, the receptacle would not be tightly closed and would fail to attain maximum rigidity. Accordingly connecting sections are provided for closing joints between the side faces and the end of the receptacle. These connecting sections, of which six are provided in the present embodiment, indicated by the reference numbers 83, 84, 85, 86, 87, and 88, are directly flexibly and integrally joined to respective sides of the polygonal end section 11, so that if desired they may be erected relative to the end section 11 by being forced against abutments during movement of the blank by a plunger, and in the manner of folding the side wall sections of the blank. Preferably one or more of these connecting sections is engaged between two side wall sections of the receptacle. For example, in the illustrated blank connecting section 84 may upon folding be enclosed between side wall sections 16 and 17, and/or side wall section 83 may be enclosed between side wall sections 18 and 15. As stated above, I deem it preferable to form joints between the groups of wall sections by overlapping full-sized side wall sections. For maximum tightness strength and neatness of appearance, it is preferable further to provide sufficient of these side wall sections to form double thickness side walls between the two or more side wall sections (herein sections 12 and 13) which are directly and integrally joined to the end section.

In the embodiment of Figs. 1 to 5, this result is accomplished, in a receptacle of eight sides, by providing fourteen side wall sections, (or twice the number of sides of the receptacle minus the number of side wall sections directly joined to the end wall). Thus each of the connecting sections 84 to 88 inclusive may be and preferably is, disposed between two full-sized side wall sections in the finished receptacle. In a finished receptacle made in this way the connecting sections are not exposed on either the inner or outer sides of the finished receptacle.

In order to manufacture receptacles rapidly, the folding of the wall forming parts (side wall sections and connecting sections) may be carried on concurrently, Fig. 2 showing diagrammatically all of the side wall forming elements of the blank in the process of being erected (by suitable plunger and abutment instrumentalities not shown) and particularly showing the two groups of side wall sections being folded into their ultimate enclosing positions relative to each other. Fig. 3, which shows the side wall forming elements more nearly completely folded, shows also the preferred relative positions of connecting sections intermediate side wall sections of opposite groups.

The fact that the end section 11 has more than four sides, and hence has interior angles between its sides greater than ninety degrees is of particular advantage in erecting and folding the side wall forming elements of the blank in a rapid and expeditious manner. Referring to Figs. 1 and 2, the formation of the receptacle involves the simultaneous folding of adjacent connecting and full-sized side wall sections, in different directions and above respective angularly related fold lines. For example connecting section 83 and the entire group of side wall sections including the adjacent section 18 are preferably in motion simultaneously, section 18 moving around fold lines 18' and 40, and section 83 moving around fold line 83'. The obtuse angle between fold lines 40 and 83' permits the adjacent edges of sections 83 and 18 to clear upon a slight folding of these sections, as shown in Fig. 2. Thus likelihood of interference between parts of the blank during folding is prevented, and permits the folding operations to be carried on with rapidity. This automatic clearing of adjacent connecting and side wall sections may be attained in a blank as shown without cutting away the connecting sections adjacent the side wall sections. Referring to Fig. 1, free outer edges of the connection sections, 83, 85, 86 and 88 are parallel to and adjacent ends of respective side wall sections and are preferably separated therefrom only by slits 99, such as those made by single cutting knives which do not remove any substantial pieces of the stock. The likelihood of thin slivers (intended to be

removed) remaining between these adjacent parts of the blank and interfering with the neat assembly of the receptacle is thus avoided, while the connecting sections 83, 85, 86 and 88 are not decreased in area by cutting away of material to provide for clearance.

This arrangement in the blank of connecting sections joined to sides of the end section, permits these connecting sections, after being folded into the planes of the side walls, and overlapped with one or more side wall sections, to be subjected to the compression utilized in fastening the side wall sections. This is of advantage in glueing together the overlapping parts of a receptacle, as the connecting sections may be affixed by pressure to the side wall sections by the same or similar instrumentalities which affix the side wall sections, and glued joints between these connecting sections and the side wall sections may be made as tight and strong as those between overlapped side wall sections.

Referring to Fig. 5 which shows a complete receptacle made in the above described manner from the blank of Fig. 1, the end section 11 of more than four sides is free intermediate its edges of any line of weakness and disfigurement of the type caused by folding flat material upon itself and subsequently unfolding it. Thus this end of the receptacle is suitable to bear advertising or decorative matter, and is furthermore strong and without tendency to buckle.

Suitable structure for closing the end of the carton or receptacle opposite to end section 11 is shown in Figs. 1 to 4 as illustrative of various types of end closures which may be employed for this last closed end. Referring to Fig. 1 inner and outer sections 90 and 97 are flexibly joined respectively to the ends of side wall sections 13 and 12. Joint-closure sections 91 and 92, preferably having, as shown, outwardly flaring side edges, are flexibly joined to ends of side wall sections 16 and 22, and triangular joint-closure sections 93, 94, 95 and 96 are flexibly joined to outer ends of side wall sections 14, 18, 20 and 24. A preferred order of closing the end closure sections is first to fold section 90 from its upstanding position shown in Fig. 4, transversely of the side walls of the receptacle into end closing position. This inner end wall section, since it conforms generally to the inner cross sectional dimensions of the carton, serves as a positioning member accurately to dispose the flexibly joined side walls in their desired angular relation and thus insure accurate sealing of the receptacle. Joint-closure sections 91 and 92 are then preferably folded over and affixed to section 90, following which the triangular joint-closure sections 93, 94, 95 and 96 are folded down and affixed. Lastly the outer section 97 is folded down and affixed to the

underlying sections and forms a complete end closure for the receptacle substantially flush with the ends of its side wall faces as shown in Fig. 5.

5 The alternate form of blank of Fig. 6 differs from that of Fig. 1 in relative proportions of the side walls and end section, in the absence of end closure elements for closing the open octagonal end of the receptacle, 10 and further in the provision of only enough side wall sections to provide overlapped joints of a width equal to that of a single side wall section rather than that of three side wall sections as in the previously described embodiment. Since, however, sections of the blank and receptacle of Figs. 6 and 7 correspond to sections of the blank and receptacle of the previously described embodiment, these sections are designated in 15 Figs. 6 and 7 by corresponding reference numerals with the addition of the letter *a*. Referring to Fig. 6 the blank shown therein includes an octagonal end section 11^a in the form of a regular octagon, having joined thereto at opposite sides, and flexibly through the provision of fold lines of increased flexibility 40^a and 41^a, side wall sections 12^a and 13^a. To side wall section 12^a are flexibly joined the side wall sections 16^a, 18^a, 20^a and 22^a while to side wall section 13^a are flexibly joined side wall sections 17^a, 19^a, 21^a and 23^a. Connecting sections 83^a, 84^a, 85^a, 86^a, 87^a and 88^a are flexibly joined to the remaining sides of the octagonal end section 11^a as in the previously described embodiment. The side wall sections and connecting sections of the blank of Fig. 6 may be erected relative to the octagonal end section 11^a and fastened 20 together in a manner similar to that described for the blank of Fig. 1, the order of folding and affixing the side wall and the connecting sections preferably being such that these sections lie in the positions shown in Fig. 7 in the completed receptacle. The receptacle of Fig. 7 which is of octagonal form is obviously suitable for use as a tray, cap or cover, which may cooperate with a similar and interfitting receptacle, or serve 25 as a cover, bottom or end for a separately formed tube.

The modified form of blank of Fig. 8 and the receptacle made therefrom and shown in following figures illustrate the application of the above described principles of my invention to receptacles having polygonal end sections of more than four sides and capable of closure in two different orders as desired for filling through either a side or an end. In the blank of Fig. 8 and in Figs. 9 to 16, wall sections are designated by reference numerals corresponding to those employed in Figs. 1 to 5 with the addition of the letter *b*.

65 Referring to Fig. 8 the blank shown there-

in includes the octagonal end section 11^b in the form of an irregular octagon and the side wall sections 12^b and 13^b joined thereto at opposite sides and defined by fold lines of increased flexibility, 40^b and 41^b. To side wall section 12^b are flexibly joined the side wall sections 14^b, 16^b, 18^b, 20^b, 22^b and 24^b, while to side wall section 13^b are flexibly joined the side wall sections 15^b, 17^b, 19^b, 21^b, 23^b, and 25^b. Connecting sections 83^b, 84^b, 85^b, 86^b, 87^b and 88^b are flexibly joined to sides of the octagonal end section 11^b intermediate the directly joined side wall sections 12^b and 13^b, connecting sections 84^b and 87^b preferably having the shape of a full side wall of the finished receptacle.

The parts of the blank of Fig. 8 thus far described are adapted to cooperate to form, if desired, a receptacle having an open top or end. In order to close this open end I prefer to provide another end section 11^c similar to end section 11^b and flexibly joined to the side wall section 12^b along the fold line 40^c. At the opposite side of this end section 11^c a flap 30 is flexibly joined thereto along the fold line 41^c. Connecting sections 83^c, 84^c, 85^c, 86^c, 87^c and 88^c are flexibly joined to sides of the octagonal end section 11^c intermediate the two directly joined side wall and flap sections 12^b and 30.

As in the blank of Fig. 1, connecting sections 83^b, 85^b, 86^b and 88^b have free edges parallel and adjacent to end edges of adjacent side wall sections and are separated therefrom only by narrow slits 99.

The blank of Fig. 8 may be formed into the open receptacle of Fig. 9 for example by the same operations involved in forming the open receptacle of Fig. 3 from the blank of Fig. 1, the parts occupying corresponding positions in the open receptacle. In folding this blank, the non-perpendicular relation of the fold lines about which side wall sections and adjacent connecting sections fold, facilitates rapid folding of these parts without interference.

The receptacle of Fig. 9 may be filled from its open top and then closed by folding over its top end section 11^c and tucking in its flap 30 and connecting sections 83^c, 84^c, 85^c, 86^c, 87^c and 88^c, the wall sections 84^c, 87^c and the closing flap 30 preferably lying face to face with side wall sections of the receptacle. Thus as shown in Fig. 11 one of the side walls of the closed receptacle formed by the cooperating wall sections 22^b, 23^b, 87^b and 87^c comprises four thicknesses of material each of which is an extension of another of the side wall sections of the receptacle. In this way a very rigid structure is obtained.

In the alternate method of forming the blank of Fig. 8 into a receptacle the flap 30 may be turned over upon the section 11^c by folding along the line 41^c and section 13^b may be laid upon flap 30, by folding along the line

40^b, and side wall section 13^b affixed to flap 30, for instance by means of pressure and previously applied adhesive, the blank thus having the collapsed tubular form of Fig. 12 5 in which it may conveniently be shipped or stored.

The collapsed tube of Fig. 12 may be opened into the open tube of Fig. 13 suitable to receive contents through either of its ends, 10 whereupon the ends of the tube may readily be closed by externally operating instrumentalities. Preferably side wall section 87^e is first folded into the end closing position of Fig. 4 then side wall sections 20^b, 22^b and 24^b 15 are folded relative to their attached side wall section 12^b and relative to each other to conform to the marginal contour of oppositely disposed end wall sections 11^b and 11^e as shown in Fig. 15. The connecting sections 20 86^b, 87^b and 88^b are then folded into end closing position overlapping sections 24^b, 22^b and 20^b, and preferably fastened in this 25 position for instance by adhesive. Side wall sections 21^b, 23^b and 25^b are then preferably folded and affixed in the positions of Fig. 10.

The alternate form of blank shown in Fig. 17 is in general similar to the blank of Fig. 8 and may likewise be formed into receptacles in two different orders of folding but is 30 provided with a smaller number of connecting section. The various sections of the blank of Fig. 17 correspond to those of the blank of Fig. 8 and accordingly are designated by the same reference numerals with 35 the addition of the letters *c* and *f*. The blank of Fig. 17 differs from that of Fig. 8 in that side wall sections 22^c and 23^c are so proportioned relative to each other and to side wall sections 87^c and 87^f that upon folding into 40 their ultimate positions side wall sections 22^c and 23^c do not overlap but substantially abut and are overlapped by sections 87^c and 87^f. Accordingly in the folding of these sections into their ultimate positions side wall sections 45 22^c and 23^c may, if desired, be folded simultaneously, instead of successively as in the case of the blank of Fig. 8.

I claim:

1. Receptacle-forming blank of foldable 50 material comprising an end section having more than four sides, a plurality of side wall sections, substantially equal in width to respective sides of said end section, said side wall sections being arranged in two groups of 55 flexibly joined sections the said sections in each group being defined by intervening fold lines adapted to mark the corners of the completed receptacle, one section of each of said groups being directly, integrally and 60 flexibly joined at an end to a side of said end section, and a plurality of connecting sections directly integrally and flexibly joined at their ends to each of the other sides of said end section, respectively, the number of the 65 side wall sections in said two groups being

equal to twice the number of sides of said end section minus two.

2. Receptacle formed of an integral sheet of foldable material and comprising an end wall of more than four sides, a pair of groups 70 of conjoined side wall sections, the said sections in each group being defined by intervening lines of increased flexibility upon which the material is folded and which mark the corners of the receptacle, sections of each 75 group corresponding in width at one end to the lengths of respective sides of said end wall, two side wall sections, one from each of said groups, being directly and integrally joined to non-adjacent sides of said end wall, 80 other side wall sections of each group extending in opposite directions around sides of the end wall to the directly joined side wall section of the other group, whereby to provide multi-thickness side walls extending from 85 one to the other of the two side wall sections which are directly joined to the end wall, and a connecting section directly and integrally joined to a side of said end wall and lying 90 face to face with a thickness of one of the said 95 multi-thickness side walls.

3. Receptacle formed of an integral sheet of foldable material and comprising an end wall of more than four sides, a pair of groups 95 of conjoined side wall sections the said sections in each group being defined by intervening lines of increased flexibility upon which the material is folded and which mark the corners of the receptacle, a plurality of sections of each group corresponding in 100 width at one end to the lengths of respective sides of said end wall, two of said side wall sections, one from each of said groups, being directly and integrally joined to respective sides of said end wall, other sections of each 105 group extending around sides of the end wall toward the other group, a section of one group being adjacent to a section of the other group in one of the side walls, and a connecting section directly and integrally joined 110 to said end wall and lying in the side wall containing said adjacent sections, said connecting section having the shape of a side wall 115 of the receptacle.

4. Receptacle formed of an integral sheet 115 of foldable material and comprising an end wall of more than four sides, a pair of groups of conjoined side wall sections the said sections in each group being defined by intervening lines of increased flexibility upon 120 which the material is folded and which mark the corners of the receptacle, a plurality of sections of each group corresponding in width at one end to the lengths of respective sides of said end wall, two of said side wall sections, one from each of said groups being directly and integrally joined to respective sides of said end wall, other sections of each group extending around sides of the 125 end wall toward the other group, a section 130

of one of said groups overlying a section of the other group to form a multi-thickness wall of the receptacle, and a connecting section directly and integrally joined to a side 5 of said end wall non-adjacent to one of the sides to which a side wall section is joined, and lying between and glued to the two overlying side wall sections.

5. Receptacle forming blank comprising a 10 side wall section, a polygonal end section of more than four sides flexibly joined at one of its sides to an end of said side wall section, another side wall section flexibly joined to another side of said end section and a second 15 polygonal end section of more than four sides flexibly joined to the opposite end of said last-named side wall section, other side wall sections flexibly joined to sides of said side wall sections, and connecting sections 20 flexibly joined to other sides of said two polygonal end sections respectively.

6. An octagonal receptacle comprising an integral sheet of foldable material in the form of an octagonal end section, two opposite 25 side groups of rectangular side wall sections, the said sections in each group being defined by intervening lines of increased flexibility upon which the material is folded and which mark the corners of the receptacle, each of 30 said groups of side wall sections having therein at least five sections, one of which is directly flexibly connected to a side of said end section, the two groups of side wall sections being folded around the said end section 35 and being fastened together at opposite sides thereof, and a plurality of connecting sections comprising integral extensions of other sides of the said end section and fastened to adjacent side wall sections.

40 Signed by me at Boston, Mass., this third day of March, 1930.

CHARLES P. WELLMAN.
